UNITED STATES PATENT OFFICE.

JESSE EARNEST KNIGHT, OF BELLINGHAM, WASHINGTON.

SPARK-ARRESTER.

No. 909,610.

Specification of Letters Patent.

Patented Jan. 12, 1908.

Application filed August 12, 1906. Serial No. 448,118.

To all whom it may concern:

Be it known that I, JESSE EARNEST KNIGHT, a citizen of the United States, and a resident of Bellingham, in the county of 5 Whatcom and State of Washington, have invented a new and Improved Spark-Arrester, of which the following is a full, clear, and exact description.

The purpose of the invention is to provide 10 novel features of construction for a spark arrester, that afford an adjustable canopy over the exhaust pipe in the smokestack of a locomotive or other portable engine, whereby a concave deflector is afforded, which is 15 connected with a spark-conductor, for the transfer of sparks from the smokestack to a point of discharge, and that, when not in service, may be contracted in diameter so as to afford a draft passage of increased 20 area when fuel combustion is to be effected by the natural draft of the stack.

The invention consists in the novel construction and combination of parts, as is 25 hereinafter described and defined in the appended claims.

Reference is to be had to the accompanying drawings forming a part of this specification, in which similar characters of reference indicate corresponding parts in all the 30 views.

Figure 1 is a sectional view of a smokestack, and an exhaust pipe therein embodying features of the invention, other details of the improvement being shown partly in 35 section and disposed mainly above the exhaust pipe; Fig. 2 is an enlarged sectional side view of a smokestack in part, and of the principal details of the invention adjusted differently from that represented for 40 said parts in Fig. 1; and Fig. 3 is a broken plan view of a smokestack and a plan view of the improved spark arrester in position within the stack.

In the drawings, 5 represents the body of 45 a smokestack of well known form, comprising a cylindrical wall, whereon is mounted an enlarged bonnet 5^a, that is covered with the usual screen wire hood 5^b. Centrally in the body 5 of the stack the exhaust 50 pipe 6 is vertically positioned, the lower portion of which, that is not shown, having the usual connection with branch-pipes that receive exhaust steam from the locomotive engine cylinders in the ordinary way.

55 In the upper portion of the exhaust pipe

6, which is cylindrical and diametrically enlarged, as at 6^a, a tubular guide 6^b is formed or secured centrally, said guide leaving steam passages *a* intervening between its outer surface and the wall of the enlargement 6^a.

A laterally-curved spark-conductor pipe 7 is a detail of the invention, and, as shown, said pipe is tapered from one end *b* thereof to the opposite end *c*. The larger end *b* of 65 the spark conductor pipe 7 is supported centrally in the bonnet 5^a and directly above the open upper end of the exhaust pipe 6 by a flat brace-bar 8, that extends across the bonnet and is secured by its ends on the side 70 wall thereof, said pipe passing through a central opening in the brace-bar wherein it is secured by suitable means. The curved and tapered conductor pipe 7 is arched above the brace-bar 8, and extends outwardly and 75 downwardly through said brace-bar, thus disposing the end *b* thereof below the latter.

Upon the end *c* of the curved conductor pipe 7 the upper end of a depending extension pipe 7^a is secured, said extension pipe 80 being preferably formed of woven wire fabric, as indicated in Figs. 1 and 2. Upon the larger end *b* of the conductor pipe 7 that is positioned below the brace-bar 8 a suitable number of spaced ears *d* are formed or secured, and upon said ears the upper ends of a plurality of plate metal segments 9 are 85 hinged by their upper ends. The similar plate metal segments 9 increase in width toward their free ends, and are so relatively 90 disposed that they lap one upon the other at their side edges when distended to form a canopy over the exhaust pipe 6, as is shown at *e* in Fig. 3.

In the guide-tube 6^b a slide-block *f* is 95 loosely fitted, and is secured on the lower end of a pusher-rod *g*, on which is secured a collar *h*, whereon like ends of a plurality of spreader arms *i* are pivoted at equal distances apart. The number of spreader- 100 arms *i* is equal to the number of segments 9, and said arms are pivoted at their remaining or upper ends on said wing-like segments respectively, as shown at *i'* in Fig. 2. It will be seen that the weight of the wings 105 or segments 9 will cause them to fold toward each other, as indicated in Fig. 2, this adjustment of parts occurring when the engine having the improved smokestack is not running.

The operation is as follows: When the canopy formed of the wind-segments 9 is in folded condition, ample space in the bonnet 5^a is afforded for free natural draft, so that a fire may be started and steam raised while the engine is standing. Upon starting the locomotive, that may be a portable or traction engine, and thus causing exhaust steam to be expelled from the exhaust-pipe 6, the force of the upward discharge of steam will distend the wings or segments 9 and form a canopy over the exhaust-pipe. As the distended canopy is of a greater width than the diameter of the stack body 5, and is concave on the lower side thereof, it will be evident that sparks and cinders that pass up the smokestack will impinge upon the lower side of the canopy; and thence be transferred through the spark-conductor pipe 7 into the depending extension pipe 7^a.

The perforated pipe 7^a may be extended down into the ash-pan of the locomotive, portable or traction engine, thus preventing the escape of live sparks upon the road bed, and avoiding danger of fire therefrom.

It will be noted that as a portion of the pipe extension 7^a passes through the bonnet 5^a, the exhaust steam may readily escape into the latter, while the sparks and cinders descend the pipe 7^a by their weight.

While the improvement is especially well adapted for service on a locomotive, portable or traction engine, it may also be utilized as a reliable spark arrester for all steam generators using an enforced draft.

Having thus described my invention, I

claim as new and desire to secure by Letters Patent:

1. The combination with a smokestack, and an exhaust pipe therein, of a normally folded canopy supported directly above the exhaust pipe, and adapted to be expanded by the exhaust steam expelled from the pipe.

2. The combination with a smokestack, and an exhaust pipe therein, of a foldable canopy, supported over the exhaust pipe and which will be distended by exhaust steam expelled from the pipe.

3. A combination with a smokestack, and an upright exhaust pipe therein, of a canopy formed of foldable wings which are adapted for distention by exhaust steam from the exhaust pipe.

4. The combination with a smokestack, an upright exhaust pipe therein, and a guide tube in the upper end of said exhaust pipe, of a curved and tapered spark conductor pipe supported over the exhaust pipe, a foldable winged concave canopy hung from an open end of the conductor pipe, and a device engaging the guide-tube and the canopy which controls the distention and folding of said canopy when it is impinged upon by exhaust steam expelled from the exhaust pipe.

In testimony whereof I have signed my name to this specification in the presence of two subscribing witnesses.

JESSE EARNEST KNIGHT.
